(57) **CLAIM**

The ornamental design for a magnetic belt, as shown and described.

DESCRIPTION

FIG. 1 is a front elevation view of a magnetic belt showing my new design with belt back piece, belt front piece and belt center magnet illustrated separately, in this specific order, for clarity;

FIG. 2 is a rear elevation view;

FIG. 3 is a top plan view;

FIG. 4 is a side elevation view;

FIG. 5 is an isometric front view; and,

FIG. 6 is an isometric rear view of a magnetic belt showing my new design.

1 Claim, 5 Drawing Sheets

FIG. 1

FIG. 2

FIG. 3
